[57] **ABSTRACT**

Acid-active and acid-stable amylase having superior amylolytic activity under acidic conditions is obtained by culturing an amylase-producing micro-organism of the Paecilomyces subgibbosum group in a nutrient medium therefor.

PROCESS FOR THE PREPARATION OF AMYLASE

This invention relates to a novel and useful amylase and to a process for the preparation of the same.

More particularly, this invention is concerned with an acid-active and stable amylase derived from a new strain of microorganism belonging to *Paecilomyces subglobosum* as novel and useful product and moreover with a process for the preparation of the said novel enzyme.

Various kinds of microorganism have heretofore been employed to produce various types of amylolytic enzyme and among them some strains had been extensively used in the industry, for example, strains of the yellow-greenish Aspergilli group such as *Aspergillus oryzae* and of the blackish Aspergilli group such as *Aspergillus usamii*, *Aspergillus awamori* and *Aspergillus niger*, a certain strain of the Rhizopus group, and bacterium such as *Bacillus substilis*.

Generally, some differences in enzymatic properties have been found between the above microbial amylase preparations.

Accordingly, it may be considered that they were used according to each characteristic property, for example, active pH range, pH-stability such as acid-stability and alkali-stability, heat-stability and amylolytic mode.

With respect to amylolytic activity, many amylase preparations derived from various microorganisms have been found to possess two kinds of typical activities, namely, dextrinogenic and saccharifying functions against starch.

Some amylase preparations possessing acid-activity and acid-stability of dextrinogenic and saccharifying functions are suitable for various uses under acidic conditions, being especially suitable as digestive enzyme which functions against dietary starch in the stomach where the gastric juice provides a strongly acidic condition.

Akaboli et al. (Symposium of Enzymatic Chemistry in Japan, Vol. 7, P. 107, 1952) reported an amylase preparation derived from *Aspergillus oryzae* to have dextrinogenic activity at pH ranging from 4.0 to 7.0 and to be easily inactivated at pH below 3.0, and, in Hakkō Kogaku Zasshi (J. Fermentation Technology in Japan), Sakamoto et al. demonstrated that Rhizopus group microorganisms produce an amylase with optimum dextrinogenic activity at about pH 5.0.

According to Minoda (J Agr. Chem. Soc. Japan, Vol. 29, P. 115, 1955, and Vol. 35, P. 479 and 482, 1961, Japanese Patent Published Specification No. 35-5046 and Agr. Biol. Chem., Vol. 37, No. 11, P. 809, 1963), amylases are derived from strains belonging to *Aspergillus niger* and among thus-obtained amylase preparations, the dextrinogenic activity is mainly indicated at pH above 4.0, the preparations being sufficiently stable under the acidic conditions.

However, commercial forms of the amylase preparations according to methods of the above, and other known commercial preparations hereinafter described, show neither desirable amylolytic activity nor stability under acidic conditions lower than pH 4.0 (cf. FIGS. 1, 2, 3 and 4 of the accompanying drawings).

In sharp contrast, the new strains, *Paecilomyces subglobosum* TPR-3811 employed in this invention can produce an acid-active and acid-stable amylase preparation which is stronger and more stable in dextrinogenic and saccharifying activities at an acidic pH of more than 3.0 and furthermore exhibits the desirable activities thereof at pH 2.5 (cf. tables hereinafter described).

Accordingly, the present invention provides new amylase preparations which are active at pH ranging from 2.5 to 6.0, in particular are stronger than the prior preparations at pH ranging from 2.5 to 3.5 and also are stable at pH ranging from 3.5 to 9.0, in particular more stable than the prior preparations at pH ranging from 3.5 to 5.0 in dextrinogenic and saccharifying activities (cf. FIGS. 1, 2, 3 and 4).

A new acid-stable digestive enzyme had heretofore been prepared by using a strain (TPR-220; ATCC No. 14572) belonging to the *Paecilomyces varioti* group, but it could not satisfactorily serve our purpose to obtain an acid-active and stable amylase preparation (cf. FIGS. 9 and 10).

As a result of the present invention, we have now discovered among the several microorganisms belonging to the *Paecilomyces subglobosum* group two new microorganisms producing amylase preparations which function at an acidic pH ranging from 2.5 to 4.5, the optimum pH being 4.0 to 4.5.

The new microorganisms, which are different from *Paecilomyces varioti* have been designated *Paecilomyces subglobosum* TPR-3810 and TPR-3811.

It is one object of this invention to isolate new microorganisms producing an acid-active and stable amylase preparation.

The main object of this invention is to obtain excellent enzyme having the above acid-active and stable amylolytic activity by employing the new microorganisms, *Paecilomyces subglobosum* TPR-3810, TPR-3811 and other strains possessing the same biological characteristics as TPR-3810 and TPR-3811.

It is still another object of this invention to obtain easily the aforesaid novel and useful amylase preparations.

The new microorganisms of this invention are isolated from wild fungi by the following screening which serves satisfactorily our purpose.

METHOD FOR THE ISOLATION OF THE STRAINS

25 1st step:

Petri-dishes, in which a modified Czapek-Dox agar culture medium:

30 carbon source:	0.5% of soluble starch;
nitrogen source:	0.5% of peptone;
inorganic salts:	0.1% of potassium dihydrogen phosphate;
	0.05% of potassium chloride;
	0.05% of magnesium sulphate;
	0.001% of ferrous sulphate

35 being adjusted to pH 3 is placed, are exposed to the atmosphere, outdoor or indoor, or to various soil samples collected in Tokyo city for some time without covers, and then 40 they are cultivated.

2nd step:

50 45 500 strains are selected from among the many strains which have thus been grown, then 50 strains are selected, which produce amylase functioning at pH 3 from among the 500 strains cultivated upon modified Czapek-Dox culture medium:

50 carbon source:	3% of glucose;
nitrogen source:	2% of peptone;
inorganic salts:	0.1% of potassium dihydrogen phosphate;
	0.05% of potassium chloride;
	0.05% of magnesium sulphate;
	0.001% of ferrous sulphate,

55 at 30°C for 3 days with shaking.

3rd step:

60 65 60 Among the 50 selected strains which produce such acid-active and stable amylase functioning at pH 3, two microorganisms producing the strongest acid-active and more stable amylase are further selected for use in this invention.

From morphological observations, the said two strains belong to the same species and besides they have quite identical characteristics in:

- the activities and properties of amylase which they produce in a liquid culture medium;
- the productivity of same pale brown pigments in the culture medium;
- the availability of nitrates.

70 75 70 The morphological characteristics of the new discovered microorganisms, *Paecilomyces subglobosum* TPR-3810 and TPR-3811 are as follows:

MORPHOLOGIES OF NEW MICROORGANISMS

Colonial observations of the microorganisms were performed with the colonies produced on agar-salt plates.

Detailed morphological studies were carried out of the mycelia growth on slide-glass.

1. Colonies:

surface . . . flat

color . . . greenish brown or yellowish brown

2. Spore forming part:

similar to genus *Paecilomyces*, sterigmata variously partly arising singly, partly two to four of them making a verticil, with some exceptional dense growing, giving an irregular penicillus-like appearance.

3. Sterigmata:

ample like shaped, usually with a constriction at center, measuring 21 by 3.5 μ on an average, slightly rough surfaced.

4. Conidia:

form a long chain from the apex of sterigmata, globose or sub-globose, sometimes elliptical, measuring 5.5 by 3.6 μ on an average, a little rough surfaced.

5. Penicillus:

typical ones are not seen.

6. Metulae or branches:

not so definite or differentiated, if any, measuring 12 by 3.5 μ on an average.

7. Conidiophore:

about the size of 20 by 4 μ on an average.

8. Macrospore:

sometimes seen in media, subglobular; 8 by 10 μ mostly.

9. Sclerotia, perithecia or ascospores . . . none.

10. Funicularly rising aerial mycelia and gelatinlike exudation as observed in the culture of *Paecilomyces varioti* . . . none.

Relative to the apparently closely related species of *Paecilomyces varioti*, detailed studies clarify the differences between them.

MORPHOLOGICAL DIFFERENCES OF NEW STRAINS
FROM *PAECILOMYCES VARIOTI*

1. Conidia:

shape . . . more globular, not so elliptical.
surface . . . a bit rougher.

2. Sterigmata:

shape . . . a little constricted at center, not so mildly tapering.
surface . . . a bit rougher.

3. Regularity of spore forming parts:

irregular, sterigmata more densely distributed sometimes, showing penicilluslike appearance.

From the characteristics mentioned above, it is considered that the new microorganisms belong to the genus *Paecilomyces*, but as to species do not fall under *Paecilomyces varioti*. They constitute a new species on the genus *Paecilomyces* and have been designated as *Paecilomyces subglobosum* TPR-3810 and TPR-3811 respectively.

PROCEDURE OF PRODUCING ACID-STABLE
AMYLASE

In accordance with one aspect of this invention, novel and useful amylase can be produced by culturing the new microorganisms, *Paecilomyces subglobosum* TPR-3810 and TPR-3811, in an appropriate nutrient medium in per se conventional manner.

According to this invention, there is established a modified culturing method which has led to good results from the fact that the obtainable quantity and activity of the amylase are essentially influenced by components of the culture medium employed.

Essentially, the medium contains a carbon source, a nitrogen source and trace inorganic elements, each in appropriate quantity, as the nutrient substances.

i. Liquid culture medium

Examples of more suitable carbon sources in the modified culture medium are 5 percent of various kinds of starch or 5

percent of maltose, but glucose, sucrose, dextrose, glycerol and wheat flour in amount of 5 percent each can also be used instead of starch or maltose.

Suitable nitrogen sources are 3 percent of peptone, and subsidiarily there can be employed raw soybean flour, defatted soybean, dried yeast, corn steep liquor in amount of 3 percent.

Suitable inorganic elements are:

Magnesium sulfate — 0.051%

Ferrous sulfate — 0.01%

10 Potassium chloride — 0.1%

Potassium dihydrogen phosphate 0.2%

Liquid culture medium is made up by mixing the above components with water. (These components are employed as main liquid culture medium or liquid culture medium for seed koji).

It is desirable to adjust the pH value of the medium to pH 6.0 after each of these substances are added into the medium.

The maximum yield and high amylolytic activity of the obtainable amylase are generally obtained with culture treatments as follows:

In culturing tank,

Aeration rate — 4/3 v/v/min.

Stirring — 350 r.p.m.

25 Temperature — 30°C

Culturing time — about 90 to 94 hours.

The medium so prepared and treated is sterilized and inoculated with *Paecilomyces subglobosum* TPR-3810 or TPR-3811 seed culture medium pre-incubated upon the medium containing the same components as above for 70 hours, after which the cultivating (submerged culture) step is carried out for 90 to 94 hours with aeration.

ii. Solid culture medium

Solid culture medium-base is made up by the following 35 components, wheat bran:chaff:water in the ratio of 5:3:4. The solid culture medium so prepared is sterilized and inoculated with *Paecilomyces subglobosum* TPR-3810 or TPR-3811 seed culture medium, the medium so inoculated is laid in state of pile and then cultivated at 30°C for about 70 hours.

40 (Similarly, these components are employed as main solid culture medium or solid culture medium for seed koji.)

SEPARATION OF THE DESIRED AMYLASE

45 Separation of a highly purified and active amylase from the cultured medium and extracted solution is carried out in accordance with the following procedure (a) or (b), adjusting the pH value to about 6.0

a. Precipitating process

Precipitation of the desired amylase is facilitated by addition of hydrophilic organic solvents such as ethanol or acetone, or ammonium sulphate.

50 When it is desired to employ the said precipitating process, the following treatment leads to good results: addition of ethanol to 65 percent final concentration or addition of acetone to 55 percent final concentration and in case of ammonium sulphate, addition thereof to 0.8 of its saturation at the final concentration.

b. Adsorbing Process

60 When it is desired to employ this method, adsorbents such as DEAE-Sephadex-ion exchanger, DEAE-Cellulose-ion exchanger and the like may advantageously be employed.

After adjusting the ion-exchanger with pH 7.0, 0.005 M phosphate buffer solution, a cultured medium or extracted solution of the amylase is adsorbed on the ion-exchanger.

The thus-adsorbed material is eluted with pH 4.0, 0.25 M sodium citrate buffer solution.

70 Thus adjusted eluate is treated by the same procedure as in the above precipitating process a) to obtain the desired enzyme.

DETERMINATION OF AMYLOLYTIC ACTIVITY

The amylolytic activity of amylase prepared by this invention (Example 1, infra) is compared with that of the following commercial amylase preparations A, B, C and D.

Amylase preparation A

amylase derived from *Aspergillus niger*
(Japanese Patent Published
Specification No. 35-3046)

commercially available in Japan as
"Sanactase."

Amylase preparation B

amylase derived from *Aspergillus aureus* (Japanese Patent Published
Specification No. 39-12284)

commercially available in Japan as
"Stalase."

Amylase preparation C

amylase derived from
Aspergillus oryzae commercially available in America
as "Mylose 100."

amylase derived from
Aspergillus oryzae commercially available in Japan
as "Taka Diastase."

Amylase preparation D

The results of the determinations are shown graphically in the accompanying FIGS. 1 to 12 and are further explained in the following preliminary explanations and in paragraphs 1 to 5.

PRELIMINARY EXPLANATIONS

FIG. 1 illustrates the activity of dextrinogenic power of the aforesaid compared amylases at various pH levels. Rec. time: 30 minutes. Rec. temperature: 40°C.

FIG. 2 shows the activity of saccharifying power of the aforesaid compared amylases at various PH levels. Rec. time: 2 hours. Rec. temperature: 40°C.

FIG. 3 shows the stability of dextrinogenic power of the aforesaid compared amylases at pH 4.5, 40°C, for 30 minutes, after pre-treatment at various pH levels, 40°C, for 30 minutes.

FIG. 4 shows the stability of saccharifying power of the aforesaid compared amylases at pH 4.5, 40°C, for 30 minutes, after pre-treatment at various pH levels, 40°C, for 2 hours.

FIG. 5 shows the effect of rec. temperature on the dextrinogenic power of the aforesaid compared amylases. Rec. pH: 4.5. Rec. time: 30 minutes.

FIG. 6 shows the effect of rec. temperature on the saccharifying power of the aforesaid compared amylases. Rec. pH: 4.5. Rec. time: 2 hours.

FIG. 7 sets forth graphically the effect of temperature on the stability of dextrinogenic power of the aforesaid compared amylases, after pre-treatment at pH 6.0, at various temperatures, for 30 minutes.

FIG. 8 sets forth graphically the effect of temperature on the stability of saccharifying power of the aforesaid compared amylases, after pre-treatment at pH 6.0, at various temperatures, for 2 hours.

FIGS. 9 to 12 inclusive sets forth comparative results obtained with amylase of this invention (Example 2, infra) vis-a-vis an amylase preparation derived from *Paecilomyces varioti* TPR-220.

FIG. 9 shows the comparative results re activity of dextrinogenic power at various pH levels. Rec. temperature: 40°C. Rec. time: 30 minutes.

FIG. 10 shows the comparative results re activity of saccharifying power at various pH levels. Rec. temperature: 40°C. Rec. time: 2 hours.

FIG. 11 shows the effect of temperature on the dextrinogenic power. Rec. pH: 4.5. Rec. time: 30 minutes.

FIG. 12 shows the effect of temperature on the saccharifying power. Rec. pH: 4.5. Rec. time: 2 hours.

EXPLANATION OF LEGENDS

In FIGS. 1 to 8 inclusive—

- ◎—◎ represents the new amylase according to Example 1
- represents amylase preparation A
- ×—× represents amylase preparation B
- △—△ represents amylase preparation C
- represents amylase preparation D In FIGS. 9 to 12 inclusive—
- represents the new amylase according to Example 2
- represents amylase from *Paecilomyces varioti* TPR-220

INTERPRETIVE EXPLANATIONS

1. pH activity curves of amylase

The digestive activity of the compared amylase preparations has been determined as shown in FIGS. 1 and 2. The amylase preparations derived from *Paecilomyces subglobosum* TPR-3810 and TPR-3811 possess dextrinogenic and saccharifying powers at pH ranging from about pH 2.5 to 6.0, in particular more excellent activity at pH ranging from pH 3.0 to 6.0, substantially stronger activities than the other compared preparations at pH ranging from 2.5 to 3.5 and their optimum pH approximately at pH 4.0 to 4.5.

On the other hand, the commercial amylase preparations A, B, C, D require pH 5.0 for optimum condition.

As result of these determinations, it is clear that the activity of the new amylase preparations of the present invention is more excellent than that of the compared commercial preparations under acidic conditions.

2. pH stability curves of amylase

The dextrinogenic and saccharifying powers of the new amylase preparations are of good stability at pH ranging from about pH 3.5 to 9.0 in comparison with the above commercial amylase preparations which require pH 5 to 9.0 as shown in FIGS. 3 and 4.

Thus, the new amylase preparations show more excellent stability and activity under acidic conditions.

3. Optimum temperature of amylolytic activity at pH 4.0 to 4.5

New amylase preparations . . . 50°C
Commercial amylase preparations . . . about 40°C 4. Heat stability of amylolytic activity at pH 4.0 to 4.5

All the commercial amylase preparations are stable at below 40°C but the new amylase preparations are more stable than the commercial amylase preparations at 50°C.

Comparative tests have also been made as to amylolytic activities and characteristics between the new strains and *Paecilomyces varioti* TPR-220, which have considerable morphological similarities.

The differences and superiority of the new amylase preparations are made clear by the following tables and facts, showing that the amylase preparations of this invention exhibit more excellent effects in dextrinogenic and saccharifying activities as shown in FIGS. 9 to 12.

45 5. Differences of the pH activity and active temperature

		pH activity		Temperature activity
		Active range	Optimum pH	
50	New amylase (according to Ex.2)	pH 2.5-7.0	pH 4.0-4.5	(Optimum temp.)
	New amylase (according to Ex.1)	pH 2.5-7.0	pH 4.0-4.5	50°C.
	Amylase of <i>Paecilomyces varioti</i> TPR-220	pH 3.0-7.0	pH 5.0	50-60°C.
55				
		Dextrinogenic power (at pH 4.0-4.5)	Saccharifying power (at pH 4.0-4.5)	
	New amylase (according to Ex.2)	70,000 unit/g.	110,000 unit/g.	
60	New amylase (according to Ex.1)	200,000 unit/g.	220,000 unit/g.	
	Amylase of <i>Paecilomyces varioti</i> TPR-220	4,000 unit/g.	13,000 unit/g.	

65 AMYLOLYTIC ACTIVITIES

		Dextrinogenic power		Saccharifying power	
		pH 2.5 unit/g.	pH 3.0 unit/g.	pH 2.5 unit/g.	pH 3.0 unit/g.
70	New amylase (according to Ex.1)	80,000	160,000	60,000	120,000
	Amylase preparation A	<	10,000	<	12,000
	Amylase preparation B	<	5,000	<	10,000
	Amylase preparation C	<	20,000	<	10,000
	Amylase preparation D	<	4,000	<	7,000

The new microorganisms can advantageously produce the acid-active and stable amylase preparations in both liquid culture medium and solid culture medium; on the contrary, *Paecilomyces varioti* TPR-220 can only produce an amylase in solid culture medium (not production in liquid culture medium).

CALCULATION OF DEXTRINOGENIC AND SACCHARIFYING POWERS

The dextrinogenic and saccharifying powers were calculated by the following determinations.

i. Starch dextrinogenic power: assaying by blue value method

1 ml. of an amylase solution was added to 10 ml. of 2 percent soluble starch solution containing a half quantity of 1/10 M sodium citrate buffer solution and kept at 40°C for 30 minutes.

Sampling up 1 ml. of the mixture, 1 ml. of 1 N-HCl was added to the mixture to stop the reaction, and further 10 ml. of N/5,000 iodine solution were added.

The sample was assayed by optical density (wave length: 660 m μ , absorption layer: 1 cm.).

A blank test was carried out by the same procedure using distilled water instead of the enzyme solution.

DEXTRINOGENIC POWER UNIT=

$$\text{Blank value} - \text{Assay value}/(\text{Blank value}) \times 1,000 \times 1/30 \times 1,000/n$$

wherein

n = mg. of enzyme preparation used.

In this determination, the unit is based on dextrinogenic power necessary for decreasing the blue color reaction in 10 ml. of 2 percent soluble starch to 0.1 percent per minute at 40°C., whereby the value is calculated as one unit and it is practically exchanged by the unit per g. of the used amylase preparation.

ii. Saccharifying power: assaying by iodine method

1 ml. of an amylase solution was added to 20 ml. of 2 percent soluble starch solution containing a half quantity of 1/10 M sodium citrate buffer solution and kept at 40°C for 2 hours.

20 ml. of N/10 iodine solution and 20 ml. of N/5 NaOH were added and then kept standing at room temperature.

After standing for 20 minutes, 4 ml. of 1 N-H₂SO₄ were added and free iodine was titrated with 0.1 N-Na₂S₂O₃.

Similarly, a blank test was carried out by the same procedure where enzyme solution was not added, after addition of iodine solution.

This unit is based on the power necessary for saccharifying 20 ml. of 2 percent soluble starch at 40°C, whereby the value is calculated as one unit when 1 mg. of glucose is produced when using 1 g. of the amylase in iodine titration.

The following examples illustrate presently preferred exemplary embodiments of the invention, but are not intended as a limitation thereof.

EXAMPLE 1

1st step:

Liquid culture medium for seed koji		
Potato starch	100 g. (grams)	
Peptone	60 g.	
Potassium dihydrogen phosphate	4 g.	
Potassium chloride	2 g.	
Magnesium sulphate	1 g.	
Ferrous sulphate	0.2 g.	

The above materials are dissolved in 2 liters of water and adjusted to pH 6.0 with conc. HCl

After sterilizing the medium at 125°C for 10 minutes, a dip of *paecilomyces subglobosum* TPR-3810 is, using a sharp platinum wire as an inoculating needle, inoculated and then pre-incubated upon the above liquid culture medium for seed koji at 30°C for 70 hours with rotary-shaking apparatus.

The pre-incubation gives a seed koji of *Paecilomyces subglobosum* TPR-3810.

2nd step:

5	Main liquid culture medium Potato starch Peptone Potassium dihydrogen phosphate Potassium chloride Magnesium sulphate Water	5 kg. (kilograms) 3 kg. 200 g. 100 g. 10 g. 100 liters

The above materials are mixed and adjusted to pH 6.0 with conc. HCl.

10 Similarly, the medium is sterilized at 125°C for 10 minutes. The seed koji pre-incubated by 1st step is inoculated upon the main liquid culture medium and cultivated in the culturing tank under the following conditions: temperature: 30°C; aeration rate: 130 liters/min.; stirring: 350 r.p.m.; cultivating time: 94 hours.

Then the cultured medium is centrifuged to separate fungi and 60 liters of supernatant containing an acid-active and stable amylase are obtained with the centrifuging.

Thus-obtained supernatant is adjusted to pH 6.0 and 130 liters of 95 percent ethanol cooled at -20°C are added into the supernatant in order to obtain a precipitation of the amylase.

The precipitate is thoroughly washed with ethanol and dried in vacuo at 30°C.

25 180 g. of powdered amylase preparation are obtained from the preparation, which has 200,000-205,000 unit/g. in dextrinogenic power at pH 4.0 to 4.5 and 210,000-220,000 unit/g. in saccharifying power at pH 4.0 to 4.5.

EXAMPLE 2

1st step:

35	Solid culture medium for seed koji Wheat bran Chaff Water	500 g. 300 g. 400 ml. (milliliters)

The above materials are mixed.

After sterilizing at 125°C for 30 minutes, a dip of *Paecilomyces subglobosum* TPR-3811 is, using a sharp platinum wire as an inoculating needle, inoculated upon the above liquid culture medium for seed koji and then pre-incubated at 30°C for 70 hours.

The pre-incubation gives a seed koji of *Paecilomyces subglobosum* TPR-3811.

2nd step:

50	Main solid culture medium Wheat bran Chaff Water	50 kg. 30 kg. 40 liters

The above materials are mixed to make the main solid culture medium base.

Similarly, the medium is sterilized at 125°C for 30 minutes.

55 The seed koji pre-incubated by 1st step is inoculated upon the main solid culture medium and layed to cultivate at 30°C for 70 hours.

250 liters of water are added to the cultured medium to extract the amylase.

60 After extracting at 30°C for 3 hours and further centrifuging, 150 liters of transparent solution containing an acid-active and stable amylase are given.

Thus-obtained solution is mixed with 330 liters of 95 percent ethanol cooled at -20°C in order to obtain a precipitation of the amylase.

65 The precipitate is washed with ethanol and dried in vacuo at 30°C. 900 g. of powdered amylase preparation are obtained from the precipitate, which has 70,000 unit/g. in dextrinogenic power at pH 4.0 to 4.5 and 110,000 unit/g. in saccharifying power at pH 4.0 to 4.5.

70 The acid-active and acid-stable amylases of the present invention are useful, by virtue of their superior amylolytic, dextrinogenic and saccharifying activities in extended fields, for example as digestive for medicaments, for pre-treatment of materials for processing foods, as enzymes for ripening materials during production, as clarificant of fermentative foods

such as beer, sake (Japanese wine), vinegar and the like, as a tenderizer of beef or corn before cooking, as well as for other purposes for which amylases are conventionally used. The instant amylases are however more especially suitable for use under acidic conditions and particularly as digestive enzyme which functions against dietary starch in the stomach where the gastric juice provides a strongly acidic condition.

A culture of *Paecilomyces subglobosum*, strain TPR-3811 is on deposit at American Type Culture Collection, Rockville, Maryland, under ATCC accession number 16492. A culture of *Paecilomyces subglobosum*, strain TPR-3810 is similarly on deposit under ATCC accession number 16493.

What is claimed is:

1. A process for the preparation of acid-active and stable amylase having superior amylolytic activities under acidic conditions, which comprises, in combination, the steps of

1st: pre-incubating a microorganisms selected from the group of *Paecilomyces subglobosum* strain TPR-3810 (ATCC 16493) and *Paecilomyces subglobosum* strain TPR-3811 (ATCC 16492) on a sterilized liquid or solid culture medium for seed koji at 30°C for 70 hours under aerobic conditions and thereby obtaining a seed koji of the *Paecilomyces subglobosum* group; and

2nd: inoculating and cultivating the thus-obtained seed koji on a main liquid or solid culture medium at 30°C under aerobic conditions until the objective acid-active and stable amylase is substantially accumulated in the culture medium, and recovering the acid-active and stable amylase from the cultured medium.

2. A process according to claim 1, wherein the 2nd step cultivation is carried out for about 70 to 90 hours.

3. A process according to claim 1, wherein the microorganism is *Paecilomyces subglobosum* TPR-3810 (ATCC 16493).

4. A process according to claim 1, wherein the microorganism is *Paecilomyces subglobosum* TPR-3811 (ATCC 16492).

5. A process according to claim 1, wherein the main liquid culture medium and the liquid culture medium for seed koji are aqueous media and contain:

a. a carbon source selected from the group consisting of starch and maltose, in a total amount of 5 percent by weight;

b. a nitrogen source constituted by peptone in a total

5

amount of 5 percent by weight; and

c. 0.05 percent of magnesium sulfate, 0.01 percent of ferrous sulfate, 0.1 percent of potassium chloride and 0.2 percent of potassium dihydrogen phosphate, all by weight.

6. A process according to claim 5 wherein the carbon source also comprises a member selected from the group consisting of glucose, dextrine, glycerol and wheat flour, the total amount of carbon source not exceeding the said 5 percent by weight, and wherein the nitrogen source also comprises a member selected from the group consisting of raw soybean flour, defatted soybean, dried yeast and corn steep liquor, the total amount of nitrogen source not exceeding the said 5 percent by weight.

10 7. A process according to claim 1, wherein the main solid culture medium or the solid culture medium for the seed koji is constituted by wheat bran, chaff and water in the following ratio:

wheat bran:chaff:water = 5:3:about 4 by weight.

20 8. In a process for the fermentative production of amylase by the culturing of an amylase-producing microorganism in a nutrient medium therefor, the improvement according to which the microorganism is a member selected from the group consisting of *Paecilomyces subglobosum* strain TPR-3810 (ATCC 16493) and *Paecilomyces subglobosum* strain TPR-3811 (ATCC 16492) and, whereby the obtained amylase is characterized by the following:

a. amylolytic dextrinogenic and saccharifying activities in a broad pH range from 2.5 to 6.0, said activities being superior to those of amylases from *Aspergillus niger*, *Aspergillus aureus*, *Aspergillus oryzae* and *Paecilomyces varioti* in the acidic pH range from 2.5 to 3.5 the optimum pH ranging from 4.0 to 4.5,

b. stability of dextrinogenic and saccharifying powers in a broad pH range from 3.5 to 9.0,

c. 70,000 to 200,000 unit/g. in dextrinogenic power and 110,000 to 220,000 unit/g. in saccharifying power in the acidic pH range from 4.0 to 4.5; and

d. heat stability at about 50°C and effective amylolytic, dextrinogenic and saccharifying activity at 40°C at pH ranging from 4.0 to 4.5.
